CARPET SWEeper CASE

Earle R. Smith, Alhambra, Calif., assignor to
Edna Cambell Smith

Application February 9, 1948, Serial No. 7,055

5 Claims. (Cl. 15—41)

1

This invention relates to carpet sweepers of the manually propelled type. More particularly the invention is directed to the provision of an improved case or housing for carpet sweepers of this type.

It is evident that the appearance of an article of this nature is a big factor in its marketability. Further the appearance is determined almost entirely by the case which substantially encloses all of the working parts. Heretofore carpet sweeper cases have been manufactured on a large scale as a unitary structure according to a preselected design. The obvious result of this method of manufacture is a limitation on the number of design modifications and a large number of sweepers of fixed design which must be marketed prior to the introduction of new design features.

In recent years manufacturers have marketed sweepers having a window framed into the top of the casing at its geometric center. Other attempts have been made to incorporate windows of various shapes and sizes into the center of the casing. All of these attempts have required "framing in," i. e. the provision of a window frame in the panelling in the top of the casing, an expensive procedure which in any event detracts from the beauty and simplicity of the casing design. To the best of my knowledge no one has been successful in producing a sweeper case on an economical basis having windows in the sides thereof. By sides, I refer to the portions of the case on either side of the longitudinal center.

I have now developed a carpet sweeper casing and particularly a chassis therefore which may be manufactured in large numbers and which lends itself to several alternative finished forms without alteration of the basic structure. Further the chassis of the invention is so constructed that the entire upper surface of the assembled case may be transparent or in the alternative any one or a number of panels may be transparent while the other panel or panels may be opaque. In addition the case of the invention is simple and economical to manufacture.

I accomplish the aforementioned objects of the invention by the provision of a chassis or framework comprising a pair of end members which are normally opaque and are fastened together in spaced relationship by a pair of side rails. A pair of additional or "top" rails across the tops of the two end members divide the curvilinear area defined by the two side rails and the upper curved edges of the end members into three substantially equal sections. To complete the casing three panels are inserted in the three

sections formed by the top rails and the side rails and are removably held therein by engagement with the rails in the manner hereinafter set forth.

5 Although in the preferred embodiment of the invention, two top rails are provided, it is equally within the contemplation thereof to provide a plurality of such rails. Thus if x additional rails are fastened between the two end members, the upper surface of the casing will be divided into $x+1$ sections and $x+1$ panels will be inserted in these sections to complete the casing.

The number of design modifications made possible by the chassis of the invention is determined by the number of sections in which the upper surface of the casing is divided. Thus in the preferred embodiment there are three panels each of which may be made of transparent or translucent plastic, or opaque metals, wood or plastic. By standardizing on the chassis construction and by varying the nature of the panels removably inserted therein, a large number of design modifications may be obtained. Three such modifications which I have found to be particularly pleasing to the eye may be as follows. In one an opaque panel is inserted in the center sections and a transparent panel in each of the side sections. In another highly pleasing design, all of the three panels are transparent in which case the entire interior of the sweeper is visible from above. Still another modification includes three opaque panels, the center panel being of white pearl to contrast with say black side panels.

The construction of the chassis and casing of the present invention will be more clearly understood from the following detailed description thereof, taken in relation to the accompanying drawing in which:

40 Fig. 1 is a plan view of the complete casing with a portion of the three panels cut away to show the construction of the chassis;

Fig. 2 is a side elevation of the case of Fig. 1;

Fig. 3 is a sectional elevation of a case taken on the line 3—3 of Fig. 1;

45 Fig. 4 is a sectional elevation of one of the top rails;

Fig. 5 is a sectional elevation of an alternative form of top rail;

50 Fig. 6 is a plan view of one of the panel members adapted to be employed in the casings shown in Figs. 1 and 8;

Fig. 7 is an elevation of an anchor strap viewed from the inside;

55 Fig. 7a is a sectional elevation taken on the line 7a—7a of Fig. 7;

Fig. 7b is a sectional elevation taken on the line 1b—1b of Fig. 7;

Fig. 8 is an end elevation of a modified casing; and

Fig. 9 is a plan view of the casings of Fig. 8.

Referring to Figs. 1, 2 and 3, the carpet sweeper case of the invention comprises a chassis 10 in which are inserted three panels 11, 12 and 13 to form the completed case. The chassis comprises the end members 16, 17, side rails 20, 21 and top rails 23, 24.

The end members 16, 17 are normally wooden but may also be fabricated of metal or plastic. The shape of the end members is best shown in Fig. 3 with reference to the end 17. The end 17 has a substantially flat bottom edge 17A and a curvilinear top edge 17B. The bottom is centrally slotted at 17C to receive a conventional brush (not shown). The curvilinear edge 17B terminates at either side in a vertical inset to receive the rabbeted side rails 20, 21 and is indented in the central portion to receive the top rails 23, 24.

The side rails 20, 21 are grooved on their upper edges at 26 and 27 respectively to receive one edge of the side panels 11 and 13. The bottom edge of each of the side rails is rabbeted to receive the flange of a conventional dust pan (not shown).

In one embodiment the rails 23 and 24 are metal strips bent generally in an S-shape as shown in section in Fig. 4. The rails thus form two longitudinal slots opening in opposite directions and in which the edges of adjoining panels are inserted. The lower leg 23A of the rail 23 is crimped inwardly at 29 to increase the mechanical strength of the rail. (See Fig. 4.)

The ends of the rails are drilled to receive the screws 30, 31, 32 and 33 (Fig. 1). As shown in Fig. 4 the upper leg of the rail 23 is provided at its end with a hole 35 which is larger than the hole 37 through the intermediate and lower legs. In this manner the head of the screw 33 will pass through the upper leg 35 and will abut against the chamfered edge of the hole 37 in the intermediate leg. This position of the screw 33 is shown in Fig. 3.

An alternative form of top rail, shown in section in Fig. 5, comprises a metal bar 28 having longitudinal grooves 28A and 28B formed therein and a countersunk screw hole 28C (Fig. 5) at each end thereof. This form of rail is affixed at its opposite ends to the opposing end members in the same manner as rails 23, 24. An inexpensive method of producing a rail as shown in Fig. 5 is by extrusion whereby the grooves may be formed during the process. In such case it may be desirable to plate the extruded rail prior to incorporation in the chassis.

The panels 11, 12 and 13 are made of a flexible material such as a thin metal or plastic and are inserted in the chassis by flexing the panel transversely so as to slip the longitudinal edges thereof into the grooves in the side and top rails.

Inasmuch as these panels are made of comparatively thin flexible material, such for example, a 30 gauge plastic sheet, it is preferable to shape the panel in the manner shown in Fig. 6 so as to impart thereto sufficient strength to prevent collapse under impact. As shown in Fig. 6 which is a plan view of one of the panels inserted in the case of Fig. 1, say the panel 11, the width of the panel at the center is greater than at either edge. For present purposes it is desirable that the panels be symmetrical so that the opposite ends thereof are of the same width. Thus the dimension H as shown in Fig. 6 is identical for all of the tapered edges. The center of the panel 11

has a width which is in excess of the width of the ends by a value of 2H. The increased width in the center portion causes the panel to bell outwardly along its longitudinal center when it is inserted within the chassis as shown in Fig. 1.

By holding the ends of each panel down against the upper edge of the end members a crown is formed in the central longitudinal portion of the panel. The effect of the crown thus formed is to impart a high degree of rigidity and impact resistance to the otherwise flexible panel.

To hold the panel ends down as described I provide a pair of anchor straps overlying the panel ends and the upper edges of the end members 16 and 17. The anchor strap 38 is shown in Figs. 1 and 2 mounted on the end member 17 and is shown in detail in Figs. 7, 7a and 7b. A similar anchor strap (not shown) is mounted over the end member 16. The strap 38 is anchored to the side rail 20 by a screw 39 and at its opposite end to the side rail 21 by similar means. The strap 38, as shown in Figs. 7, 7a and 7b comprises a band 38A having a depending flange 38B running the entire length thereof and a centrally depending lip 38C. The flange 38B lies along the outer surface of the end member when the strap is mounted as shown in Figs. 1 and 2 and serves not only to strengthen the strap but also to give a neat appearance to the assembled case. The lip 38C which is slightly concave on its lower edge presses down against the central panel between the top rails 23 and 24. The lip 38C thus serves the dual purpose of holding the end of the center panel down against the edge of the end member and forming a neat appearing molding.

As shown in Fig. 3 which is a sectional elevation taken on the line 3—3 of Fig. 1, the central longitudinal portion of the panel 11 is bulged away from the contours of the upper edge 17B of the end member 17, while the narrower end of the panel is held snugly against the edge 17B by the anchor strap 38.

As hereinbefore mentioned, the three panels 11, 12 and 13 may be made from any semi-flexible material such as thin plastic, metal, wood veneers and the like, or of different colors of the same material. Furthermore, each of the panels 11, 12 and 13 may be made of different material or different types of the same material or two of the panels may be made of the same material or type of material and the third panel of a different material or different type material. Thus, in one embodiment of the invention the panels 11, 12 and 13 may all be made of transparent plastic in which case the interior of the sweeper is completely visible from above. Alternatively the side panels 11, and 13 may be of transparent plastic and the central panel 12 may be made of an opaque plastic, metal or wood. In a third embodiment the side panels 11 and 13 may be made of an opaque plastic, metal or wood and the central panel 12 may be made of a transparent plastic. Alternatively all of the panels may be opaque and of the same or different color. In this manner a number of sweeper designs may be produced from a single standard chassis. This feature of the invention is particularly important to large manufacturers who normally market several types of sweepers varying in price and quality. By making the chassis of all of the various types thus marketed in accordance with the present invention, the different series of sweepers may be made to have a different external appearance by the character and type of panels inserted therein. Standardization thus achieved reduces the manufacturing costs of all of the models.

A modification of the chassis shown in Fig. 1 is illustrated in Figs. 8 and 9. The modified chassis comprises the end pieces 40 and 41 joined together by side rails 42, 43. As in the foregoing embodiment of the invention the side rails 42, 43 are grooved along their upper edges to receive a panel in the manner hereinbefore described. In this embodiment of the invention a rigid central panel 45 is affixed to the central portion of the curved upper edge of the end members 40 and 41 by means of a plurality of screws or nails (not shown). The panel 45 may be wood or plastic and in the latter case may be transparent or opaque. Further the panel may have veneered thereto any desired decorative materials such as trade mark insignias or the like. The longitudinal edges of the panel 45 are grooved at 46 and 47 to receive the edges of the panels 50 and 51, the other edges of which are inserted in the side members 42 and 43. The panels 50, 51 in the embodiment shown in Figs. 6 and 7 are identical to the panel 11 shown in Fig. 5. Thus when inserted, as shown in Fig. 6, the flexible panels 50 and 51 are crowned outwardly in their central portion to impart structural strength thereto. The longitudinal crown is formed by reason of the greater width of the central portion of the panel (see Fig. 6).

In the embodiments here shown flexible metal strips 58 and 59 are fastened along the upper edge of the end members after insertion of the panels by hand flexing the same into the appropriate grooves. Thus the strip 58 is fastened at either end to the sides 42 and 43 by means of the screws 60 and 61 respectively. The metal strip is bent at 63 and 64 to curve back upon itself to fit within the grooves 46 and 47 respectively in the central panel 45. The purpose of the metal strips 58 and 59 is to hold the end edges of the flexible panels 50 and 51 down against the upper edge of the end members 40 and 41. This produces the crown in the center portion of the panel as described above.

I have described and illustrated a new type of carpet sweeper case having a chassis and a number of interchangeable panels removably inserted in the chassis. By standardizing on the construction of the chassis innumerable casing designs may be produced by varying the types and colors of panels employed. Many types of panels may be used other than the specific ones herein described. However, the scope of the invention

is such as to contemplate the use of any such panels or combinations thereof in the chassis.

I claim:

1. A carpet sweeper case comprising a pair of end members each having a curvilinear upper edge terminating at either side in a substantially vertical edge adjoining the bottom edge, two side members affixed to the corresponding vertical edges of the two end members and joining the end members in spaced relationship, a longitudinal groove in the upper edge of each of the two side members, two rails affixed at opposite ends to the upper edges of the two end members and dividing the area defined by the upper edges of the side members and the end members into three sections of substantially equal area, each of the rails having two longitudinal grooves, the two grooves in each of the rails opening in opposite directions, a separate flexible panel held in each of the sections by engagement of the longitudinal edges thereof with the grooves in said rails and said side members, and a metal strap extending across the upper edge of each of the end members to hold the panel ends thereagainst.

2. A carpet sweeper case according to claim 1 wherein each of the flexible panels is broader in the center than at the edges so as to form a longitudinally extending central crown in the panel when the ends of the panel are held down against the end members.

3. A carpet sweeper case according to claim 1 wherein all of the panels are transparent.

4. A carpet sweeper case according to claim 1 wherein the central panel is opaque and the two side panels are transparent.

5. A carpet sweeper case according to claim 1 wherein all of the panels are opaque.

EARLE R. SMITH.
